(57) **CLAIM**

I claim the ornamental design for a handle for a pick, as shown and described.

DESCRIPTION

FIG. 1 is a perspective view of a handle for a pick embodying my new design.

FIG. 2 is a first side view of the handle shown in FIG. 1. FIG. 3 is a second side view of the handle shown in FIG. 1. FIG. 4 is a third side view of the handle shown in FIG. 1. FIG. 5 is a fourth side view of the handle shown in FIG. 1. FIG. 6 is a first end view of the handle shown in FIG. 1; and, FIG. 7 is a second end view of the handle shown in FIG. 1. The elements shown in broken lines are included for the purpose of illustrating environment and form no part of the claimed design.
